SECRET TELEGRAPHIC SYSTEM.

1,356,701.

Specification of Letters Patent. Patented Oct. 26, 1920.

Application filed June 24, 1918. Serial No. 241,608.

To all whom it may concern:

Be it known that I, AUGUSTUS J. EAVES, a citizen of the United States, residing at New York, in the county of New York, 5 State of New York, have invented certain new and useful Improvements in Secret Telegraphic Systems, of which the following is a full, clear, concise, and exact description.

10 This invention relates to telegraph systems, and more particularly to systems for rendering secret telegraphic service.

The principal object of the invention is 15 the provision of a telegraph system wherein means is provided for preventing the intelligent interception of a message while it is being communicated between two distant stations.

In accordance with the invention means is 20 provided which is responsive to the actuation of a transmitting mechanism for causing the operation of additional means whereby the character impulses constituting a message are divided between a plurality of 25 conductors extending between two distant stations.

To the end that the foregoing objects may be attained the present invention contemplates the employment of electroresponsive 30 devices respectively under the control of telegraphic transmitting and receiving equipments located at remote points on a line circuit, the arrangement to be such that message currents of one or more telegraphic 35 channels may be switched or interspersed between a plurality of line conductors extending between such remote points. Although the telegraphic messages of the various channels would be unintelligible to persons 40 who may tap either or all of the line conductors, the automatic functioning of the devices of this invention will, nevertheless, result in each message being properly reproduced through the control of an associated 45 receiving equipment. Since the present system provides a system to baffle the efforts of any one who may seek to intercept a message under transmission it may be properly referred to as a secret telegraphic system.

50 This invention is illustrated diagrammatically in the accompanying drawing, and for the sake of clearness, only so much of a telegraphic equipment has been shown as

will be necessary to a ready and clear understanding of the system.

In the drawing (Figure 1), there is shown an equipment suitable for carrying on so-called "two-way" service, in twofold capacity, over two main line conductors arranged in a manner suitable for practising the features of this invention. In Fig. 2 there is shown an alternate arrangement which differs from the arrangement shown in the first figure principally through the employment of duplex equipments for the 65 line conductors. An alternate arrangement shown in Fig. 3 differs from the arrangement shown in Fig. 1 principally with respect to details in the organization of the 70 apparatus.

In describing the operation of this system attention will first be directed to Fig. 1 of the drawing, wherein the reference character A indicates telegraphic equipment at one station which is connected by means of two 75 line conductors L¹ and L² with a similar equipment B at a second station. At the first station A a telegraphic group C comprising a transmitting key 4, a line relay 5 and an electromagnet 6 which may be in the 80 form of a reading sounder or a relay device suitable for the reception of signaling currents, is associated for communicating with a similar group D comprising a key 44, a line relay 45 and a sounder 46 at the second 85 station B. Similar telegraphic communications may be carried on by means of a key 7, a line relay 8 and a sounder 9, indicated as a group E at the first station, with a group F comprising a key 47, a line relay 48 and a 90 sounder 49 at the second station. At the station A three polar relays 10, 16 and 19 are connected to be controlled by momentary currents which may be set up, as will presently appear, in a secondary winding 15 of 95 a current transformer 13. The relay 10 serves as a pole changer in controlling the connecting of oppositely poled batteries 11 and 12 with a local circuit formed serially through a primary winding 14 of the transformer 13, the winding of the sounder 6 and the contacts of the line relay 5. The relays 16 and 19 are arranged to reciprocally control the switching of the sets C and E from one to the other of the line conductors L¹ 100 and L².

At the second station B a somewhat similar arrangement is formed of three polar relays 50, 56 and 59, connected to be controlled by momentary currents in a secondary winding 55 of a transformer 53. The relay 50 is connected to act as a pole changer in connecting oppositely poled line batteries 51 and 52 through a circuit formed by the primary winding 54 of the transformer 53, the key 44, the line relay 45, and, during the time the equipment is in the position in which it is shown in the drawing, over the contacts 57 of the relay 56, the line conductor L¹, thence over the contacts 17 of the relay 16 at the station A, the winding of the line relay 5 and the key 4 to earth. In a manner corresponding with the service of the relays 16 and 19 at the first station the relays 56 and 59 at the second station serve to reciprocally switch the telegraphic sets D and F from one to the other of the line conductors L¹ and L². As shown in the drawing, during the time the sets C and D may be joined over the line L¹ the sets E and F will be joined by way of the contacts 20 and 60 of the relays 19 and 59, respectively, over the line conductor L². In a reciprocal manner, during the time the polar relays 16 and 19, 56 and 59 may be standing in positions opposite to those shown the sets C and D will be joined by way of the contacts 18 and 58 of the relays 16 and 56, respectively, and the line conductor L², while the sets E and F will be connected over the contacts 21 and 61 respectively of the relays 19 and 59 by way of the line conductor L¹.

The polarized relays at each station are non-biased; therefore their armatures will remain in either position to which they may be moved by a momentary impulse of operating current. It may also be pointed out that the time constant of operation of the relays 5, 45, 8 and 48 is ordinarily lower than the time constant of operation of the polar relays; therefore in the operation of the system a line relay may be initially operated by current routed over one line conductor, following which, the polar relays may so quickly switch the line connections that the line relays will not have sufficient time in which to release and may therefore continue operated by current routed over the other line conductor.

In more specifically considering the operation of this system a few transmitting operations will be assumed and traced through their various successive steps. As a first example, let it be assumed that while the equipment is at rest in the position in which it is shown, at the set D the transmitting key 44 is opened, preparatory to sending a message. This operation first interrupts the line circuit as already traced from the battery 51, and this cessation of current

through the winding 54 of the transformer 53 induces a momentary current in the secondary winding 55 of this transformer. At the station A this interruption of the line current permits the line relay 5 of the set C to release and disconnect the local circuit whereby cessation of current from the battery 11 through the primary winding 14 of the transformer 13 induces a momentary current in the secondary winding 15 of this transformer. The effect of the induced impulse in the transformer at each station operates the associate polar relays, causing their armatures to assume the bias or position opposite to that in which they are shown. At the station A the relays 16 and 19 thereby connect the set C to the line conductor L² and the set E to the line conductor L¹, while the relays 56 and 59 at the station B connect the set D to the line conductor L² and the set F to the line conductor L¹. At each station the third polar relays 10 and 50 respectively disconnect the batteries 11 and 51 and prepare circuits from the batteries 12 and 52. Therefore, assuming that the key 44 is now moved to its closed position current from the battery 52 will complete circuit over the path already traced through the line relay 5 at the first station. This line current in flowing through the transformer winding 54 at the station B and in operating the line relay 5 to close the local circuit through the transformer winding 14 at the station A, although causing a momentary current to be set up in the respective secondary windings 15 and 55 of these transformers has no effect with respect to the polarized switching relays, since the opposite polarity of the batteries 12 and 52 with respect to the batteries 11 and 51 results in the induced currents having a polarity or direction corresponding with the direction of the induced currents which resulted from the interruption of current through the primary windings of the transformers, as already described. Accordingly the associated polar relays at each station will be unaffected by the transformer currents corresponding with actions taking place through the closure of the key 44, but will continue in the position to which they may have been biased due to the circuit effects which resulted from the opening of this key. If now the key 44 is again opened, cessation of the positively poled current from the battery 52 in the transformer winding 54 and corresponding cessation of current from the positively poled battery 12 in the transformer winding 14 will respectively induce currents in the secondary windings 15 and 55 of such direction that the associated polar relays at each station will be operated and bias their armatures to the positions in which they are shown in the drawing. The line conductors will ac-

cordingly be transposed with respect to the sets C and D, and E and F, while the batteries 12 and 52 will be disconnected and circuits respectively prepared from the batteries 11 and 51.

From the foregoing description it will be clear that during the time messages may be under transmission from the set D to the set C the key 44 also serves as a master in controlling the switching of the line and local circuits at each station, in order that the secret service features of this system may be carried out. It will also be obvious that during the time messages may be under transmission from the set D at the second station to the set C at the first station or in a reverse direction between these sets, messages may be transmitted either from the set E to the set F or from the set F to the set E. This is possible since the switching relays at each station operate in a relatively simultaneous relation, thereby insuring that during the time the associated sets C and D may be connected over the line conductor L¹ the associated sets E and F will be connected over the line conductor L², and vice versa.

In transmitting from the set C to the set D the key 4 serves as a master in initiating operations whereby the polar relays at each station will respond in providing the secret service effects. Since the key 4 at the station A effects operations identical to the operations of the key 44 at the station B, in opening and closing the same line circuit, it will be clear from the descriptions already given that the master control by the key 4 is typical of the master control by the key 44, and therefore, further description of these operations will not be necessary.

With regard to the connective relation of the transformers and their respectively associated polar relays it will be mentioned that instead of this relation being in accordance with the arrangement assumed for purpose of illustration, in the foregoing descriptions the connections may be so arranged that the polar relays will respond to current induced at the instant the pole-changer relays 10 and 50 respectively complete circuit to either one of their associated batteries. Under this arrangement the polar relays would move their armatures following each closure of either the key 4 or the key 54, no response of these relays taking place at the instant either of the keys may be opened. Therefore in transmitting messages in either direction between the master sets C and D the first portion of each impulse would be transmitted over one line conductor, while the remainder of the same impulse would be transmitted over the other line conductor. Such relation of the operating circuits is possible through the difference in the time constant relation between

the polarized relays and the line relays, as already referred to. For the last assumed relation of the polar relays and their respective transformers a design or an adjustment whereby the line relays may operate quickly 70 under energization and release slowly under deenergization constitutes a desirable feature of the present system, and conversely, for the first assumed relation in which the polar relays respond at moments the key of 75 either master set is opened a design or adjustment of the relays whereby they may respond slowly under energization and release quickly under deenergization, constitutes a preferred condition for the operation 80 of the system under this relation. It is possible, however, to successfully operate the system by depending entirely upon the inherent differences in the time constant of operation between relays of suitable polar- 85 ized type and so-called neutral or non-polarized type.

In operating the system according to the relation wherein the switching relays respond at moments the transmitting key on 90 either master set may be closed the service results may be briefly summarized as follows: First, portions of the currents whereby individual impulses may be transmitted between the sets C and D are deleted with 95 respect to either line conductor; second, similar deletion may also take place with respect to currents forming individual impulses which may be under transmission between the sets E and F; and third, complete 100 impulses forming irregular fragments of messages under transmission between the latter sets may be interspersed between such currents of the first sets as form portions of individual impulses. Therefore, it will be 105 readily apparent that in case the line conductors may be tapped it would be possible to receive only an incoherent and heterogeneous jumble of impulses, impossible of translation. As a further safeguard, however, the line conductors may be remotely 110 routed, one conductor from the other, or one conductor may be routed through a cable while the other conductor may be carried in the form of an "open" wire line along the 115 same right of way. By this arrangement it would not be possible for both of the line conductors to be tapped, and therefore, the cryptic form of the signals which it would be possible for any one to obtain surreptitiously from a single one of the line conductors would be augmented and improved, through the absence of the impulses and portions of impulses carried by the other line conductor.

Referring to Fig. 2 of the drawing, in addition to the equipment shown in the first figure, duplex equipments are provided whereby in addition to the two-way service possible between the sets E and F the trans- 130

mitter set C at the station A may send to a receiving set D at the station B, while a transmitter set H at the latter station may send to a receiving set I at the former station. In this arrangement three different channels may be in operation at the same time, and the transmitting set H alone serves as the master set whereby the polar relays of the secret service may be controlled. In describing these control operations the key 44 controls a pole-changer relay 62 and a secret control relay 63. The relay 62 controls the inclusion of oppositely poled line batteries 64 and 65 with the polar relay 45 which is arranged with an artificial line AL to form a differential duplex equipment. Such outgoing currents, although neutralized and non-effective in the line relay 45, may traverse the contacts 57 of the switching relay 56, the line conductor L¹, the contacts 17 of the relay 16 at the first station, thence through a polar line relay 5 which is associated with an artificial line AL to form a second differential or polar duplex wherein the currents from the distant station, as traced, may disturb the duplex balance and cause the armature of this relay to be reciprocated to correspond with the polarity of the incoming currents. The line relay 5 controls a local circuit which includes a sounder 6, the primary winding 14 of the transformer 13 and the contacts of the switching relay 10 through which the circuit may be switched from one to the other of the batteries 11 and 12. Assuming for purpose of illustration that while the various equipments are at rest in the position shown, at the master set H the transmitting key 44 is opened, the relay 62 thereupon releases to connect the positively poled battery 65 over the circuits already traced to the relay 5 at the first station and biases the armature of that relay to its idle contact to thereby disconnect the local circuit already traced through the sounder 6. Cessation of current through the winding 14 of the transformer 13 induces a momentary current in the secondary winding 15 whereby the polarized switching relays 10, 16 and 19 will be operated in the same manner and for the same control purposes as already described for the corresponding circuits in the first figure. At the station B, coincident with the release of the relay 62, the relay 63 also restores to disconnect the local battery circuit through the winding 54 of the transformer 53. Cessation of current through the winding 54 induces a momentary current in the secondary 55 whereby the polarized switching relays 50, 56 and 59 are operated in the same manner and to establish circuit changes similar to those already described in connection with the corresponding relays of the equipment shown in Fig. 1. Closure 65 of the key 44 causes the operation of the

relays 62 and 63, thereby respectively establishing the negative battery 64 to cause the distant line relay 5 to close its local circuit and to connect the battery 52 through the transformer winding 54. At the relay 5 the local circuit including the transformer winding 14 now stands completed from the battery 12. Since the polarity relation of the batteries with the respective transformers is in opposite direction with respect to the current present at the instant the circuits were interrupted the impulse induced in the secondary windings will be in the same direction as the last impulse and therefore the respectively associated switching relays will not be affected but continue in the positions to which they were last biased, in a manner similar to that described in connection with the first figure.

In transmitting from the set C the key 4 controls the pole-changer 32 whereby the line batteries 34 and 35 may be connected to act over the duplexed circuit and cause the line relay 45 to work the associated receiving device 46. As well understood, the duplex equipments provide that service from the transmitting set C may be entirely independent from, and carried on simultaneously with, service from the transmitting set H. Therefore, it is necessary that the telegraphic traffic be distributed in such a manner that the master set H may be continuously busy in order to render the secret service switching operations effective.

In situations where the amount of traffic would make it desirable, duplex equipments typical of the equipments C and I may be substituted for the equipments E and F, thereby providing for a capacity of four channels which may be operated simultaneously between the station A and the station B.

The effectiveness of the secret service as already pointed out in connection with the arrangement shown in Fig. 1 is also present with the arrangement shown in the second figure, and it may be pointed out that in addition the increased amount of telegraphic traffic possible with the duplexed arrangement serves to render the cryptographic effects even more intricate and involved.

Referring to Fig. 3 of the drawing this arrangement differs from the arrangement shown in Fig. 1 in that the transformer 53 at the station B is controlled in a local circuit connected through the contacts of the line relay 45 of the set D. It will be obvious that by this arrangement the same secret service results as already described may be attained, and that either the transmitting key 4 of the set C or the transmitting key 44 of the set D may serve as masters with respect to controlling the operations of the secret service switching relays. The de-

tailed descriptions already given in connection with Figs. 1 and 2 are deemed to be sufficient to render further description of the third arrangement unnecessary.

5 Referring to the fact that manually operated telegraphic equipments have been illustrated in the drawing it will be understood that such equipments were chosen merely as a matter of convenience and that any suitable type of the many automatic transmitting and receiving systems may be substituted for the manual equipments without departing from the spirit of this invention.

What is claimed is:

15 1. In a system of secret telegraphy, a plurality of conductors extending from a first to a second station, means for providing a plurality of telegraphic channels between said stations, and means controlled through the transmission of impulses over a certain one of said channels to divide the impulses therefrom between said plurality of conductors and likewise to divide the individual impulses of the other of said channels between said plurality of conductors.

20 2. In a system of secret telegraphy, means for providing a plurality of telegraphic channels between remote stations, electroresponsive means at each station, and means controlled by the transmission of messages on one of said channels to vary the relation of said plurality of channels one with another.

25 3. In a system of secret telegraphy, a plurality of line conductors, means for controlling a plurality of channels in signaling over said line conductors, and means controlled by the transmission of signals over certain of said channels for reciprocally varying the relation of said channels with respect to said plurality of line conductors.

30 4. In a system of secret telegraphy, a plurality of duplexed line conductors, means for providing a plurality of telegraphic channels over said line conductors, and means controlled by the operation of certain of said channels for reciprocally varying the relation of said channels with respect to said plurality of duplexed line conductors.

35 5. In a system of secret telegraphy, remote stations, a plurality of conductors joining said stations, pluralities of transmit-

ting and receiving equipments to provide 55 a plurality of channels for communication between said stations, a plurality of relays for varying the relation of said telegraphic channels with respect to said plurality of line conductors, current transformer means 60 controlled in the working of certain of said telegraphic channels for controlling the operation of said relays, and further means controlled by said transformer for varying the control effect of said transformer. 65

6. In combination with a telegraph system a plurality of conductors extending between a first and a second station, a plurality of relays at each of said stations, a plurality of telegraphic channels completed 70 through the contacts of said relays, and means responsive to the transmission of a message over one of said channels for operating said relays to thereby divide the individual impulses of a message between said 75 plurality of conductors.

7. In a system of secret telegraphy, a first station, a plurality of transmitting and receiving equipments at said station, several polar relays and a transformer at said station, a remote station having equipment typical of said first station, a plurality of line conductors joining said stations, and means reciprocally controlled by one of said telegraphic equipments at each station for 80 controlling the operation of said polar relays, means controlled by certain of said relays for varying the connective relation of said telegraphic equipments with respect to said line conductors, and means controlled 85 by other of said polar relays for varying the effect of the control as established by said transformers.

8. In combination with a telegraph system, a plurality of conductors extending between a first and a second station, a plurality of relays at each of said stations normally operative by a current flow in one direction, and means responsive to the transmission of a message over one of said channels for reversing the direction of current flow through said relays to thereby divide the impulses of a message between said 90 plurality of conductors. 95

In witness whereof I hereunto subscribe 100 my name this 19th day of June, A. D. 1918. 105

AUGUSTUS J. EAVES.
